TELEMETERING SYSTEM

Wilhelm Ziegenbein, Berlin, Germany, assignor to
 General Electric Company, a corporation of
 New York

Application October 21, 1938, Serial No. 236,363
 In Germany November 13, 1931

5 Claims. (Cl. 171—95)

My invention relates to systems in which a voltage having alternating and continuous components is provided from an alternating-current source. The invention relates particularly to systems of this character wherein a voltage supplied to a utilization circuit and having alternating and continuous components is produced from an alternating-current source by means including electric valve devices, for example, arc discharge devices functioning as valve means.

In accordance with my invention two transformers having different high output voltages and connected in opposed relation on the secondary side are supplied from the alternating-current source, and an electric valve connected in parallel with the secondary of one of the transformers is arranged to short circuit the latter secondary during one-half of the supply voltage wave or during a portion of the half wave.

20 The novel features which are considered to be characteristic of my invention are set forth with particularity in the appended claims. My invention itself, however, both as to its organization and method of operation together with further 25 objects and advantages thereof may best be understood by reference to the following description taken in connection with the accompanying drawing wherein Fig. 1 is a diagrammatic representation of my invention in its broadest aspect; 30 Figs. 2 and 3 illustrate respectively the application of my invention to a telemetering system and to a system for testing certain apparatus such as a current transformer; Figs. 4 and 5 illustrate an 35 application of the invention to remote control uses; and Fig. 6 is a diagrammatic representation of a modification of my invention.

Referring to Fig. 1 the circuit arrangement in accordance with my invention illustrated therein includes two transformers 10 and 11 having 40 primaries 12 and 13 supplied in parallel from an alternating-current source and secondaries 14 and 15 arranged in opposing relation. The transformers 10 and 11 are wound for different high 45 terminal voltages which may be adjusted to desired magnitudes by any suitable transformer regulating means. An electric valve means designated by the numeral 16 is connected in parallel with one of the secondaries, for example, with secondary 15. Preferably, but not necessarily, the valve means is connected across the secondary of that one of the transformers, 11 in the present case, which has the lower winding ratio. The valve means 16 preferably comprises a space 50 discharge device 17 including means indicated

generally by the numeral 18 for controlling the potential applied to control electrode 19 and thereby controlling the discharge, or the initiation of the discharge in device 17 during the positive half wave of the voltage supplied from the alternating-current source to transformer 11. The secondaries 14 and 15, in series, are connected through leads 20 and 21 to any desired utilization circuit.

In operation of the system illustrated in Fig. 1, 10 voltage from the alternating-current source is impressed on the primaries of transformers 10 and 11. Since the secondaries 14 and 15 are connected in opposing relation and since the secondary voltages of the two transformers are of different value, an alternating voltage which is the resultant of the two secondary voltages exists between the opposite secondary terminals 22 and 23 of the transformers and in the entire circuit including the utilization circuit. The magnitude of this alternating voltage is determined by the difference in voltage ratio of the two transformers.

If now the valve timing control means 18 which is preferably adjustable is so adjusted as to make the valve device 17 conducting, this device then 25 short circuits the secondary 15. The timing control may be so adjusted as to make the valve 30 conducting during all or a portion of each positive half wave of the alternating supply voltage. The magnitude of the short circuit current in 35 secondary 15 may be limited to a required amount in any suitable manner, as by increasing the leakage of the transformer 11. The length of the period at each positive half wave of voltage in secondary 15 during which the device 17 is conductive and therefore effective to short circuit the secondary 15 is thus determined by the adjustment of the valve timing means 18, which 40 controls the potential of control electrode 19.

The wave form of the alternating voltage due to secondary 15 of the transformer 11 is therefore distorted at each positive half wave of the latter voltage by reason of the short-circuiting of secondary 15 by the valve 17 which causes the 45 voltage from secondary 15 to become substantially zero during all or a portion of this half wave period. Correspondingly, the above-mentioned alternating voltage which is the resultant of the voltages produced by the opposed secondaries 14 and 15, is distorted. It is only on one side of the zero line, in the present case the positive side, that the half waves of the voltage due to secondary 15 are suppressed wholly or in part by the 50 short circuiting means.

The above-mentioned resultant voltage therefore contains a continuous voltage component the magnitude of which is regulated as desired by means of the valve timing control. The output alternating voltage of either of the transformers 10 and 11 may also be changed as desired by the provision of suitable transformer regulating means.

In Fig. 2 the numeral 24 designates the source, for example a power station, of a given quantity to be measured which may be the power output of the station. The power source 24 may supply the transformers 10 and 11 through lines 25. The valve timing control means 26 controls the space discharge device 17 through the control electrode 19, being adapted to be energized in accordance with the voltage and power output of power source 24. The voltage in the utilization circuit 27 therefore contains alternating and continuous voltage components, the continuous voltage component varying in response to the power output of source 24. A measuring instrument 28 of any suitable form adapted for indication in response to the ratio between the alternating and continuous voltage components of a voltage impressed on the instrument is connected in the utilization circuit 27. Any change in the quantity to be measured at 24, in the present case any change in the power output of a power station, is then indicated by the instrument 28.

The system illustrated in Fig. 2 may be used for telemetering purposes. For example, if between two power stations normally supplying separate networks a shift of the power supply of a given network from one power station to another is required under certain conditions, the arrangement illustrated in Fig. 2 may be utilized for indicating at one station the power conditions at the other station. The measuring instrument 28 may be placed for this purpose at a station (not shown) remote from the other station designated by 24, the two transformers 10 and 11 and the valve means being located, as illustrated, at this latter station. The power conditions at the station 24 may then be continuously supervised from the remote station by reference to the instrument 28.

In Fig. 3 the transformers 10 and 11 are adapted to be supplied from an alternating-current source through a switch 29. A voltage containing alternating and continuous voltage components is supplied to a utilization circuit 30 by means of transformers 10 and 11, and valve means 16 comprising space discharge device 17 controlled by the valve timing adjusting device 18, all in the same manner as set forth in connection with Fig. 1. The output voltage of one of the transformers, as transformer 10, is preferably made adjustable as by adjustable means 31 for the primary 12. In the utilization circuit 30 is connected an apparatus 32 to be tested which is of a type of apparatus in which an alternating current ordinarily flows which contains a direct current component. Such an apparatus may be, for example, a current transformer. By changing the ratio of transformer 10 by adjusting means 31 and by controlling the short circuiting effect of valve means 16 on secondary 15 of transformer 11 by the valve timing adjusting device 18, any desired ratio of the continuous voltage component to the alternating voltage component in the voltage impressed on the apparatus 32 which is to be tested, and any desired magnitude of these components may be readily obtained.

In Fig. 4 a remote control apparatus indicated generally by the numeral 33 is connected in the utilization circuit 34 of a system identical with that illustrated in Fig. 1 for supplying a voltage comprising alternating and continuous voltage components to a utilization circuit. The remote control apparatus 33 comprises a device 35 responsive to the ratio between the alternating and continuous voltage components in the utilization circuit 34, and a space discharge device or amplifier 36, the output circuit of which is connected to any desired remote control circuit and the input circuit of which including the control electrode 37 is adapted to have impressed thereon a bias potential in response to the voltage component ratio determined by ratio responsive device 35. In the system shown in Fig. 4 the bias potential impressed on control electrode 37 is controlled from ratio responsive device 35 through the medium of mechanical means indicated conventionally by 38.

Fig. 5 illustrates a system for remote control which is identical in all respects with the system illustrated in Fig. 4 except that in Fig. 5 the bias potential impressed on control electrode 37 of space discharge device 36 is controlled from ratio responsive device 35 by any suitable electrical means designated conventionally by 39 connected to device 35 by leads 40.

In operation of the systems illustrated in Figs. 4 and 5, by suitable adjustment of the valve tuning control 18 and, if desired, of the output voltage of either of the transformers 10 and 11, the discharge in space discharge device or amplifier 36 is controlled through the voltage ratio responsive device 35 and the bias control means 38 or 39. The output of space discharge device 36 which supplies any desired remote controlled device is, therefore, correspondingly adjusted.

Application of my present invention is not restricted only to the system disclosed herein in which the transformers are single phase. By including other transformer and valve means the invention may be applied to systems including any desired polyphase transformer or similar arrangements.

Fig. 6 illustrates a three phase system in accordance with the invention. Two three-phase transformers 41 and 42 are provided having primaries 43 and 44 supplied in parallel from a three phase alternating current source, and having secondaries 45 and 46, the individual windings of one secondary, as 41, 48 and 49 of secondary 45, being respectively in opposed relation with the corresponding windings 50, 51 and 52 of the other secondary 46. The transformers 41 and 42 are wound for different terminal voltages as in the case of the transformers of Fig. 1. Electric valve means 53, 54 and 55 are connected respectively in parallel with the windings of one of the secondaries, as, in the present instance, with the windings 50, 51 and 52 of secondary 46. A means indicated generally by the numeral 56 is provided for controlling the potentials applied to the control electrodes of the valves, and thereby controlling the discharge, or the initiation of the discharge in the valves during positive half-waves of the voltage supplied from the alternating current source to the transformer 42. The pairs of secondary windings in series, 47 and 50, 48 and 51, and 49 and 52, are connected through leads 57, 58 and 59 to any desired utilization circuit. Operation of the system illustrated in Fig. 6 will be readily understood from the hereinabove

description of operation of the system illustrated in Fig. 1.

My invention has been described herein in particular embodiments for purposes of illustration.

5 It is to be understood, however, that the invention is susceptible of various changes and modifications and that by the appended claims I intend to cover any such modifications as fall within the true spirit and scope of my invention.

10 What I claim as new and desire to secure by Letters Patent of the United States is:

1. In combination, two transformers each having a secondary winding, means to connect said secondary windings in series, means to produce 15 opposing alternating voltages of different magnitude in said secondary windings, an electric valve means connected across one of said secondary windings and adapted to short circuit said one of the windings, and means to cause said valve 20 to become conductive during at least a portion of a half cycle of each voltage cycle in said one of said secondary windings whereby the voltage in said one of said windings is reduced during said portion.

25 2. In combination, two transformers each having a secondary winding, means to connect said secondary windings in series, means to produce opposing alternating voltages of different magnitude in said secondary windings, an electric 30 discharge device having an anode-cathode circuit and a control electrode, said anode-cathode circuit being connected across one of said secondary windings, and means to cause said device to become conductive during at least a portion of a 35 half cycle of each voltage cycle in said one of said secondary windings including means to control a potential impressed on said control electrode.

3. In combination, a source of an electric quantity 40 to be measured, two transformers each having a secondary winding, means to connect said secondary windings in a circuit including said secondary windings in series, means to produce opposing alternating voltages of different magnitude 45 in said secondary windings, an electric valve means connected across one of said secondary windings, means responsive to said quantity to be measured to cause said valve to be conductive during at least a portion of a half cycle of each voltage cycle in said one of said secondary windings whereby the voltage in said one of said windings is reduced during said portion.

tive during at least a portion of a half cycle of the voltage in said one of said secondary windings whereby the voltage in said circuit includes an alternating component and a continuous component, and measuring means connected in said circuit responsive to the ratio between said components.

4. In combination, an alternating-current source, two transformers each having a secondary winding, means to energize said transformers 10 from said source, means to connect said secondary windings in series, said transformers being so arranged that the output voltages thereof are of different magnitudes and in opposition, an electric valve means connected across one of said 15 secondary windings, means to cause said valve to become conductive during at least a portion of a half cycle of each voltage cycle in said one of said secondary windings, an electric apparatus adapted to be traversed by a current containing 20 an alternating component and a continuous component, and means to connect said apparatus in series with said secondary windings.

5. In combination, an alternating-current source, two transformers each having a secondary winding, means to energize said transformers from said source, means to connect said secondary windings in series, said transformers being so arranged that the output voltages thereof are of different magnitude and in opposition, an electric 30 valve means connected across one of said secondary windings, means to cause said valve means to become conductive during at least a portion of a half cycle of each voltage cycle in said one of said secondary windings thereby to produce a 35 voltage having alternating and continuous components, and an apparatus adapted to supply power to a remote control circuit, said apparatus including means connected in series with said secondary windings and responsive to the ratio 40 between said alternating and continuous components, a space discharge device including a control electrode connected to said remote control circuit, and means in operative relation with said ratio responsive means to control the potentials impressed on said electrode in accordance 45 with said ratio.

WILHELM ZIEGENBEIN.
